ART OF ORNAMENTED KNITTED WEARING APPAREL MANUFACTURE

Urban T. Marr, Appleton, Wis., assignor to
 Zwicker Knitting Mills, Appleton, Wis., a corporation of Wisconsin

Application October 24, 1938, Serial No. 236,689

13 Claims. (Cl. 66—201)

This invention relates to improvements in the art of ornamented knitted wearing apparel manufacture, and more particularly to knitted articles of wearing apparel having incorporated therein design ornamentations, and to the method of producing the same.

Certain articles of wearing apparel, such as gloves, mittens, scarves and the like, which are knit in tubular seamless formation, have heretofore been produced on knitting machines, but where it was desired to have certain surface portions of the articles bear ornamentations, these ornamentations have had to be incorporated by slow and tedious hand operations in the nature of crocheting.

Heretofore a rather unsatisfactory method was devised of producing machine knit articles of wearing apparel with ornamentation wherein the decorated areas have been knit by machine operations. However in said previous method knitting floats on the inside of the blanks always result. If these knitting floats are long they are obviously objectionable as fingers, etc. easily catch therein. If the knitting floats are of lesser length there is an undesirable restriction in the size or extent of the pattern or decorated area which can be obtained.

With these objections and difficulties in mind, the present invention provides for the production of knitted articles having designs or ornamentations incorporated therein by machine knitting in a manner so that the knitting floats are interlocked with or laid under certain of the strands of the body fabric with the elimination of long knitting floats, there being no restrictions on the size, shape, or character of the incorporated design areas.

A further object of the invention is to provide an ornamented knitted article and method of producing the same characterized by jersey or single stitch jacquard float designs, wherein, during the knitting, two yarn feeds are supplying strands for the knitting of the body fabric while another feed supplies the yarn for the pattern which is knit over the floats made by both of the strands from the first-mentioned feeds.

It is another object of the present invention to provide an ornamented knitted article and method of producing the same wherein the design is completely fastened into and intermeshed with the knitted fabric proper and so secured that there is no possibility of there being dropped stitches or loose ends of the design strands, whereby a design of any desired width and type

or character can be knitted into the knitted article.

A further object of the invention is to provide a knitted article and method of forming the same wherein a design may be incorporated in the knitted fabric in a unique manner which does not require any take-up or tension on the design forming strand or strands.

10 A further object of the invention is to provide a knitted article with machine fashioned design areas therein, and method of producing the same, which is simple, inexpensive and commercially expeditious, and which is well adapted for the purposes described.

15 With the above and other objects in view, the invention consists of the improved knitted article and method of producing the same, and its parts, combinations and steps, as set forth in the claims, and all equivalents thereof.

20 In the accompanying drawing in which the same reference characters indicate the same parts in all of the views:

Fig. 1 is a diagrammatic view of a portion of a knitted article fabric, looking at the reverse side thereof, and showing a design forming thread or strand in knitted, design forming association therewith;

Fig. 2 is a fragmentary view of the fabric of a knitted article showing machine knit designs therein;

Fig. 3 is a fragmentary view of an article forming tubular blank of knitted fabric showing the condition of the same as it is taken from the machine with particular reference to the unfastened portion of the design threads before severance, the tubular blank being shown reversed as to its normal condition for use and as to the condition in which it leaves the machine; and

40 Fig. 4 is a fragmentary view of a longer blank turned through half a circle and showing the unfastened portions of the threads for several designs, such threads being severed and also showing the knitting floats which produce the several separate designs.

In the present invention the fabric is of tubular seamless formation and is knit on an open head, cylinder knitting machine having a plurality of yarn or thread feeds. The articles formed in this fashion may be gloves, mittens, or similar articles of wearing apparel.

The method of knitting the article fabric with the design or pattern therein is subject to ordinary variations of machine operation, depending on the character of the stitch, type of yarn

utilized, and the size and character of the applied pattern or design, but essentially the method employed is as follows: During the course of the operation of the machine for knitting the cylindrical blank, at least two of the machine yarn feeds are employed for feeding to the blank forming needles the yarn for the body fabric. At a proper time during the knitting of the body fabric one or more strands of yarn from one or more additional feeds are led to the machine and are operated on by proper needles in the machine to knit into the fabric the stitches for the design or pattern which may be in any suitable configuration, of any desired width and size, and in any selected color or colors.

In Fig. 1 there is depicted semi-diagrammatically and in enlarged or magnified form a fragment of the body fabric of a knitted article with design forming stitches incorporated therein. In this view there is represented the manner in which the design stitches for a simple pattern are associated with the body fabric stitches. The yarn strand for the design stitches extending from a feed (not shown) is indicated by the letter x while the yarn strands for the body fabric extending from other feeds (not shown) are indicated in the various courses by the reference characters A1 to L1 inclusive, it being appreciated that the fabric is in a cylinder machine and the strand courses referred to are in circular formation.

In the knitting machine utilized, certain selected design forming needles are thrown into and out of operation and these needles, in the present exemplification, operate on the strands in the following manner: The body portion of the fabric or blank is knit in a one by one float stitch wherein the various courses A1, B1, C1, D1, E1, F1, G1, H1, I1, J1, K1, and L1 make loops in the odd numbered vertical rows designated 1, 3, 5 and 7. Courses B2, C2, D2, E2, F2, G2, H2, I2, J2, K2, and L2 make loops in the even numbered vertical rows designated 2, 4, 6 and 8. At a certain point in the fabric the design strand x is to be interknit therewith and as illustrated the incorporation of said design strand x commences in about the E course. It will be noted that course E1 is formed with loops in the vertical rows 1, 3, 5 and 7, and the strand in said course floats over rows 2, 4, 6 and 8. Course E2 forms loops in the vertical rows 2, 4, 6 and 8, and floats over rows 1, 3, 5 and 7, thereby providing an open space in row 4 in the E course wherein the pattern may start. The pattern forming strand x , as previously mentioned, is fed from another source and the ends of the yarn x are laid under the floats made in the E1 course and over loops 2, 4, 6 and 8, this being accomplished automatically during the process of knitting the blank by throwing into operation proper tucking needles, as will later appear.

In the F courses it will be observed that course F1 forms loops in the vertical rows 1 and 7 and floats over rows 2, 3, 4, 5, 6 and 8. Course F2 forms loops on rows 2, 6 and 8 and floats over rows 1, 3, 4, 5 and 7. As a result the strands of courses F1 and F2 float over rows 3, 4 and 5, thereby providing three open spaces for the pattern yarn x , and the ends of this yarn are laid under the floats made by the F1 course and are laid over loops 2, 6 and 8. The arrangement in the G and H courses is the same as that just described in connection with the F courses.

When the I courses are reached it will be ob-

served that courses II forms loops on rows 1, 3, 5 and 7 and floats over rows 2, 4, 6, and 8. Course I2 forms loops in rows 2, 6 and 8 and floats over rows 1, 3, 4, 5 and 7. Consequently an open space for the pattern yarn x is provided in the loops in the 4 row in the I courses. It will therefore appear that the pattern yarn x will be knit independently at the following points: in the 4 rows of the E courses; in the 3, 4 and 5 rows of the F, G and H courses; and in the 4 row of the I courses. As to courses E1 and E2, F1 and F2, G1 and G2, and H1 and H2, the yarn will be floated at the same points where the x strand is knit into the fabric.

The number of times that the design forming strand x is laid under a float is determined by the ultimate width of the pattern. As the blank forms and progresses the design forming strand x encircles the blank from the last point of fastening in one course to the first point of fastening or securing in the next course. Consequently the pattern is formed on a full float stitch.

In order that the securing of the pattern strand x may be understood, the following explanation applies: The pattern is started by strand x which extends from the proper feed, knitting into and on the fabric with reference to course E-row 4. Said strand x is at that time being held in the same course by the needles for rows 1 and 7 in a tuck stitch position, thus having D1 and E3 strands on the hooks of the needles of the 1 and 7 rows at the same time. The number of such needles being used for this purpose is determined by the size of the pattern, with as many needles being used on each side of the pattern as may be desired; these being spaced so that all will knit off on the various I courses. Said needles can be inserted through the pattern area as well as on each side of the pattern, if the floats of the pattern so demand. It should next be observed that the needle of vertical row 1 in the E course had engaged strand x , and said strand, which was held as a tuck stitch, is dropped off and forms a float over the needle of row 1. The strand at course E1 floats over the needle of row 2, thereby tying in the float of strand x from the needle of row 1 to the needle of row 4. The actual pattern is started by the needle No. 4 of course E. The strand of course E1 then knits on the needle of the row 3 and floats over the started pattern at the needle of row 4 and knits on needle 5. It also floats over the needle of the 6 row which serves to tie the float knitted by the strand x between the needle of row 5 and the needle of row 7. The strand next drops off the tuck stitch on row 7 and floats over the needle of row 8, which serves to tie in the float of strand x between row 7 and the next needle that is utilized to hold a tuck stitch (not shown). The strand of course E2 then follows and knits on the needles of rows 1, 6 and 8 and floats over the needles of rows 1, 3, 4, 5 and 7, which needles have nothing to do with the tying in of the floats, but only help to keep the strand x against the inside of the fabric and to produce a clear, smooth pattern.

Fig. 3 represents a fragmentary view of a piece of tubular fabric knit according to the method just described to accomplish one of the design formations indicated at 12 in Fig. 2. This fragment of fabric is inside-out relative to its condition upon removal from the machine and relative to the position in which it is normally used in wearing apparel. Upon removal of the

blank in the condition shown in Fig. 3, the floats 13 are connected and extend over a portion of the inverted exposed face of the fabric, as shown. To prepare the fabric for use said floats should be severed and trimmed and this is accomplished as shown in Fig. 4 wherein the float strands 13 and 13' are first severed centrally and then are additionally trimmed relatively close to their points of securement in the fabric. Fig. 4 shows the blank turned through half a circle and discloses the incorporation of several of the pattern areas 12 and 12' in the fabric and formed by the association of the strands x and x' with the body fabric strands, which strands, in said area, are floats.

A fragment of the finished fabric, reversed as to Figs. 3 and 4, is shown in Fig. 2 wherein the knitted body fabric 14 has incorporated thereon a pair of design or ornamentation areas 12 and 12' independently accomplished in the manner previously described. It will be observed that the design strands x and x' are knit over the floats of the body fabric forming strands and the ends of the design strands are laid under certain floats of the body fabric. This absolutely insures against unraveling or dropped stitches. Even after the floats 13 and 13' of the pattern are severed and trimmed, the design areas are nevertheless tightly secured in the fabric and the strands of the same will not pull out. While one type of design has been illustrated and described, it is obvious that the design can be of any type or pattern and of any size or width and can be incorporated wherever desired in the body fabric and the fabric may be formed with a plurality of independent designs of various characters.

The fabric thus knit may be used for certain forms of knitted wearing apparel and is particularly adapted for gloves and mittens. The strands may be of any suitable type of yarn, thread, string or the like, and the design may be applied with any of the same type of materials and in single or multiple strands and of single or plural colors. The entire article is completely knit and finished on the machine and can be produced efficiently and economically and the design areas therein can be formed without limitations and will simulate the more expensive forms of knitted fabrics which are subsequently ornamented by hand operations.

In the finished article the design strand is fastened under the floats of the body strands on opposite sides or margins of the design area.

It will be understood that numerous changes may be made in the details of operation and construction without departing from the spirit of the invention, as contemplated by the following claims.

I claim:

1. A knitted fabric comprising two body strands, one of which is knitted in alternate wales and floated across intervening wales, and the other of which is knitted in intervening wales and floated across alternate wales, said fabric having a design area in which both of said body strands are floated, said design area comprising a third strand which is knit in one or more wales and courses, said third strand overlying the floats of said body strands and being held by floats of a body strand on both sides of said design area in each course in which it is knit.

2. A knitted decorated fabric comprising a plurality of body strands, one of which is knitted in alternate wales and floated across intervening

wales, and another of which is knitted in intervening wales and floated across alternate wales, said fabric having a decorated area in which all of said body strands are floated, said decorated area comprising a third strand which is knit in one or more wales and courses, said third strand overlying the floats of said body strands and said third strand being held by floats of a body strand on opposite margins of said decorated area in each course in which it is knit.

3. A knitted article comprising two body strands, one of which is knitted in alternate wales and floated across intervening wales and the other of which is knitted in intervening wales and floated across alternate wales, said article having separated and independent design areas in which both of said body strands are floated, said design areas each comprising a third strand which is knit in one or more wales and courses, said third strand overlying the floats of said body strands throughout each of the design areas, and being held by floats of a body strand on both sides of the design areas in each course in which it is knit.

4. A knitted fabric comprising two body strands, one of which is knitted in alternate wales and floated over intervening wales, and the other knitted in intervening wales and floated over alternate wales, and a third strand associated with portions of the body strands to form a design area, said third strand being held under the floats of a body strand on both sides of the design area in each course in which it is knit.

5. The method of producing a knitted designed fabric which consists in the steps of knitting two body strands, one in alternate wales only and the other in intervening wales only, and producing a design area on said fabric by floating both of said body strands across the design area and knitting a third strand in one or more wales and courses, with the third strand overlying the floats of the body strands, and with the floats of a body strand holding the third strand at opposite sides of the design area.

6. The method of producing a circular knitted fabric with separate and independent design areas, which consists in the steps of knitting a plurality of body strands, one of which is knitted in alternate wales only and floated across the intervening wales, and another of which is knitted in intervening wales only and floated across the alternate wales, and producing design areas on said garment by floating both of said body strands through the design areas and knitting an additional strand through the design areas in a manner to overlie the floats made by both of said body strands, and with the floats of a body strand holding said additional strand on both sides of the design areas in each course in which it is knit.

7. A plain knitted tubular fabric comprising two body yarns, one of which is knit in alternate wales and floated across intervening wales, and the other of which is knit in said intervening wales and floated across said alternate wales, said fabric having a design area in which a third yarn only is knit in a plurality of wales and courses, both said body yarns being floated behind said third yarn at said design area, said third yarn being floated coursewise at each side of said design area, floats of said third yarn being held by floats of one of said body yarns adjacent said design area on both sides thereof in each course in which said third yarn is knit.

8. A plain knitted tubular fabric comprising two body yarns, one of which is knit in alternate wales and floated across intervening wales, and the other of which is knit in said intervening wales and floated across said alternate wales, said fabric having a design area in which a third yarn only is knit in one or more wales and courses, both said body yarns being floated behind said third yarn at said design area, said third yarn being floated coursewise at each side of said design area, floats of said third yarn being held by floats of one of said body yarns adjacent said design area on both sides thereof in each course in which said third yarn is knit.

9. A circular knitted fabric, comprising two body strands, one of which is knitted in predetermined wales and the other of which is knitted in predetermined wales and floated across other wales, said fabric having a design area in which both of said body strands are floated relative to selected wales, said design area being developed from a third strand which is knit in one or more wales and courses, said third strand overlying the floats of said body strands throughout the design area and being held by floats of a body strand laterally of the margins of said design area in each course in which it is knit.

10. A circular knitted fabric, comprising two body strands, one of which is knitted in predetermined wales and the other of which is knitted in predetermined wales and floated across other wales, said fabric having a design area in which both of said body strands are floated relative to selected wales, said design area being developed from a third strand which is knit in one or more wales and courses and which cooperates with at least one of the body strands in forming a predetermined design configuration, said third strand overlying the floats of said body strands throughout the design area and being held by floats of a body strand laterally of the design area in each course in which it is knit.

11. A circular knitted fabric, comprising two body strands, one of which is knitted in predetermined wales and the other of which is knitted in predetermined wales and floated across other wales, said fabric having a design area in which both of said body strands are floated relative to selected wales, said design area being developed from a contrasting third strand which is knit in one or more wales and courses and which cooperates with at least one of the body strands in forming a predetermined design configuration with contrasting areas, said third strand overlying the floats of said body strands throughout the design area and being held by floats of a body strand laterally of the design area in each course in which it is knit.

12. A knitted article, comprising two body strands, one of which is knitted in alternate wales and floated across intervening wales, and the other of which is knitted in certain wales, both of said body strands being floated across predetermined wales, and a third strand associated with portions of the body strands to form a design area, said third strand being knitted in the wales in which both of the body strands are floated and being held laterally of the design area by the floats of one of said body strands.

13. A knitted article in which part of the blank contains two body strands, one of which is knit in alternate wales and floated across intervening wales, and the other of which is knit in certain wales, both of said body strands being floated across predetermined wales, and an additional strand or strands knit in the predetermined wales in which both body strands are floated, the additional strand or strands being held tight to the blank by the floats of one of the body strands at the margins of the design area in each course in which said strand or strands are knit.

URBAN T. MARR.
